UNITED STATES PATENT OFFICE.

WALTER L. YOUNG, OF NEWPORT BEACH, CALIFORNIA.

WELL-DRILLING BIT.

1,095,062.

Specification of Letters Patent. Patented Apr. 28, 1914.

Application filed October 6, 1913. Serial No. 793,763.

To all whom it may concern:

Be it known that I, WALTER L. YOUNG, a citizen of the United States, residing at Newport Beach, in the county of Orange and State of California, have invented a new and useful Well-Drilling Bit, of which the following is a specification.

At present it is customary to bifurcate the cutting edge of well drilling bits by cutting away the middle of said cutting edge to form a notch or concave extending several inches toward the top of the tool and as the tool requires sharpening it is found necessary to take the tool from the well where the sharpening is usually done to a machine shop, so that the notch can be cut away with minimum expense. The expense, time and labor thus absorbed is a great item and an object of this invention is to avoid the cost thus entailed upon the operator and to so construct a drill of bifurcated character that the furcations can be readily renewed at the well.

A further object is to provide a well drilling bit of maximum length for repeated re-sharpening at the well, without excessive weight.

I regard this invention as pioneer in that the drill is made of a ladder-like form consisting of side rails united at the top by the usual drilling bit head having the usual taper screw stem and having below the head cross bars that resemble the rounds of a ladder and which hold the side members or rails in true relation to each other, but which cross-bars can be readily cut away from time to time as the furcations are shortened so much as would, under the old method, require deepening of the notch between said ends, and I do limit the invention to the exact construction.

The accompanying drawings illustrate the invention.

Figure 1 is a side elevation of a drill constructed in accordance with this invention. Fig. 2 is a longitudinal section on line α^2 , Figs. 1 and 5. Fig. 3 is an elevation looking at the edge of such drill. Fig. 4 is a fragmental side elevation of the drill when the same has become greatly worn and ready for sharpening. Fig. 5 is a cross section on line α^6 , Figs. 1, 2 and 3. Fig. 6 is a longitudinal section of a modified form.

The top end of the drill is constructed with a strong body section or head 1 having the taper-threaded stem 2 corresponding to

those on drills of ordinary construction, and is integral with parallel side rails 3, 4, which terminate in the cutting tips 5, 6 that are constructed and sharpened in accordance with the usual practice. Integral with said side rails are the cross bars 7 connecting said rails at intervals; recesses, preferably open spaces 8, being provided between said cross-bars, so that the general appearance of the drill body below the upper section 1 is that of a ladder. The cross bars 7, corresponding to the rounds of the ladder, may be of any suitable width and length determined by the size and nature of the bit, and the inter-bar spaces 8 are likewise proportioned. Between the cross bars and the inter-bar spaces may be two inches across the bars to four inches across the spaces. The lower notch 9 is formed by the inside edges of the lower ends of the side rails and by the bottom edge of the lowermost cross bar, which in the process of sharpening will be concaved on its under-side to supply the preferred construction of bit.

In practical use as the tips 5 and 6 become worn they are sharpened from time to time until the concave 9 is too shallow for satisfactory use, and then when the bit is heated for the purpose of sharpening, the lower round or cross bar 7 will be cut away, thus utilizing the lowermost one of the spaces 8; and this is continued from time to time until the upper solid end of the bit is reached. All this is easily accomplished by using the ordinary bit sharpening means at the well and without the necessity of taking the bit to the machine shop as heretofore.

The inter-cross-bar spaces are usually entirely open as shown in Fig. 1, but where desired a thin web 10 (see Fig. 6) may be formed, the same being of greatly reduced thickness so that as the sharpening process proceeds, such web may be readily cut away, thus leaving an open space or notch between the tips of the bit.

The nature of the invention is such that the bit rotates in the hole more freely because it does not meet with so much resistance from the thick mud which has been necessarily mixed up in drilling the hole; and the mud and water in the hole are mixed more thoroughly and with greater facility so that the mass is thinner and the resistance to the operation of the drill is thereby lessened, and mud can be more easily removed from the well by means of the bailer. These

advantages arise from the open nature of the body of the bit, the same being provided in the preferred form with one or more openings of comparatively large dimensions so that during operation the tool may rotate in the hole after the usual way except more freely as solid parts of the tool will pass through the thin mud more easily than to turn the entire mass of thick and sticky mud as heretofore with bits having no such openings therethrough.

I claim:—

1. A well-drilling bit comprising side rails terminating at one end of the bit in cutting tips; and cross bars connecting the rails at intervals.
2. A well-drilling bit comprising side rails terminating at one end in cutting tips; the space between the rails being recessed at intervals;

ervals; and cross bars connecting the rails 20 at the sides of the recesses.

3. A drilling bit consisting of a head provided with a stem, two side rails integral with the head and terminating in cutters; and cross bars connecting said side rails at 25 intervals.

4. A well-drilling bit having a head, side rails extending downward from the head, and cross bars uniting the side rails at intervals between the head and the tips, said 30 tips being sharpened.

In testimony whereof, I have hereunto set my hand at Newport Beach, California, this 29th day of September, 1913.

WALTER L. YOUNG.

In presence of—

C. H. WALLACE,
WALTER W. WHITE.
